HOBBING MACHINE

John Cetrone, West Orange, N. J.

Application May 22, 1942, Serial No. 444,135

10 Claims. (Cl. 90—4)

This invention relates to new and useful improvements in gear hobbing machines.

The invention proposes an arrangement for automatically separating the hob from the work upon the completion of the work so that the hob feed slide may be returned to its starting position without damaging the work.

More specifically, it is proposed that a stop rod support the height adjustment micrometer which is mounted on the hob support slide, and that means be provided for bodily lowering said stop rod when said hob feed slide reaches its finish position. This will permit the hob feed slide to be returned to its start position without interference between the hob and the work.

Another feature of the invention resides in the provision of a flexible shaft for connecting the drive wheel of the gear hobbing machine with the hob shaft so that the hob feed slide may reciprocate while the work merely rotates. The invention contemplates constructing the flexible shaft from several rigid sections which are slidably connected and which are also associated with flexible couplings.

Another feature of the gear hobbing machine resides in improved means for accurately setting the hob at a slight angle to be properly aligned with the pitch of the helix of the work being cut. It is proposed that the hob shaft be mounted in a bearing which is pivotally supported to pivot in a horizontal plane, and that means be provided for adjusting said bearing to various selected pivoted positions to accurately obtain the angle of the hob desired.

The invention also contemplates a new and novel arrangement for supporting and operating the covers for the feed change gears and the index change gears of the gear hobbing machine, whereby the covers may be easily and quickly opened and closed, singly or simultaneously, as desired.

Another feature of the gear hobbing machine resides in the provision of a steel ball to act as a thrust bearing for the work arbor in the tailstock spindle of the machine.

Still another feature of the gear hobbing machine resides in the provision of means whereby the clutch which controls the hob feed slide may be set into and out of operation so that certain resilient means be capable of urging the feed hob slide to a starting position in a pre-selected condition of the clutch. Specifically, it is proposed that when the clutch is opened the resilient means be capable of moving the said hob feed slide to the said starting position.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front elevational view of the gear hobbing machine constructed in accordance with this invention.

Fig. 2 is a plan view of Fig. 1.

Fig. 3 is a fragmentary rear elevational view 15 of Fig. 1.

Fig. 4 is a fragmentary enlarged detailed view of a portion of Fig. 3.

Fig. 5 is a fragmentary vertical sectional view taken on the line 5—5 of Fig. 2.

Fig. 6 is a fragmentary enlarged sectional view taken on the line 6—6 of Fig. 3.

Fig. 7 is a fragmentary enlarged sectional view taken on the line 7—7 of Fig. 3.

Fig. 8 is a fragmentary enlarged vertical sectional view taken on the line 8—8 of Fig. 2.

Fig. 9 is a fragmentary horizontal sectional view taken on the line 9—9 of Fig. 8.

Fig. 10 is a horizontal sectional view taken on the line 10—10 of Fig. 8.

Fig. 11 is a fragmentary end view looking in the direction of the line 11—11 of Fig. 9.

Fig. 12 is a fragmentary enlarged vertical sectional view taken on the line 12—12 of Fig. 2.

Fig. 13 is a horizontal sectional view taken on the line 13—13 of Fig. 12.

Fig. 14 is a fragmentary vertical sectional view taken on the line 14—14 of Fig. 12.

Fig. 15 is a horizontal sectional view taken on the line 15—15 of Fig. 14.

Fig. 16 is a fragmentary enlarged vertical sectional view taken on the line 16—16 of Fig. 2.

Fig. 17 is a vertical sectional view taken on the line 17—17 of Fig. 16.

The gear hobbing machine, in accordance with this invention, includes a housing 23 which is mounted on a tray 21 supported on a base 22. The housing 23 has a top recessed portion 23 across which the work arbors 24 and 25 extend. The hob 26 for operating on the work 27 which is mounted between the work arbors 24 and 25 is located beneath the work 27. The hob 26 is indirectly supported upon a vertical hob support slide 28 which in turn is mounted on a horizontal hob feed slide 29. The hob 26 is connected to and driven by a main drive pulley

or wheel 30. The pulley or wheel 30 is connected by an endless belt 31, or other drive, with an electric motor 32 which is mounted within the base 22. This electric motor 32 is shown supported on a support plate 33 which is pivotally mounted at one end upon a bracket 34. The other end of the support plate 33 is connected with a bolt 35 which is vertically slidably mounted in the top portion of the base 22 and through the tray 21.

A spring 36 is coaxially mounted on the bolt 35 and acts between the bottom wall of the tray 21 and the support 33 for resiliently urging the support 33 downwards so as to maintain the tension of the belt 31. The electric motor 32 is provided with a three step drive pulley 37 which is complementary to the three steps of the main drive pulley or wheel 30. The base 22 has a door 38 by which the interior is accessible. At this point it may be well to state that the gearing hobbing machine must be provided with the usual liquid coolant circulating system for circulating the usual coolant fluid over the work and hob during the operation of the machine. However, this mechanism forms no part of the invention and will therefore not be described in this specification.

The hob 26 is fixedly mounted upon a hob shaft 39 which is rotatively supported in a bearing housing 40 horizontally pivotally mounted by a trunnion 43 engaging a pair of horizontal spaced flanges 41 and 42 on the vertical hob support slide 28. More specifically, the slide 28 has said pair of horizontal spaced flanges 41 and 42 projecting from one face between which said bearing housing 40 is located. Said vertical trunnion 43 is mounted centrally on the bearing housing 40 and passes through complementary receiving openings in said flanges 41 and 42 for accomplishing the horizontal pivotal mounting of said bearing housing. There is means for releasably clamping the bearing housing 40, and thus indirectly the hob shaft 39, in selected pivoted positions about the trunnion 43. This means includes clamp screws 44 mounted on the top flange 41 and abutting the top of the bearing housing 40. When these clamp screws are loosened the bearing housing 40 is free to pivot.

Means is provided for adjusting said bearing housing 40 to selected pivoted positions. This means includes an expansion spring 45 located to one side of the trunnion 43 and acting in a horizontal direction between the bearing housing 40 and the hob support slide 28 for tending to horizontally pivot said bearing housing in one direction. The bearing housing 40 is provided with a lug 46 which is located on the side opposite to the side having the spring 45. This lug 46 is engaged by a fine thread screw 47, or micrometer screw, which is mounted on a lug 48 mounted on the hob support slide 28. The spring 45 functions to pivot the bearing housing 40 in one direction in which the lug 46 is engaged against the end of the fine adjustment screw 47. This permits the screw 47 to be adjusted for selecting the pivoted position of the bearing housing 40. This adjustment makes it possible to set the hob 26 to a slight angle corresponding to the helix angle of the gear teeth being cut on the work 27. When the hob 26 has been correctly set it is advisable that the clamp screws 44 be tightened to lock the bearing housing 40 in its position.

The hob shaft 39 is connected to the main

drive pulley or wheel 30 by a flexible shaft 50. This flexible shaft 50 is formed from several rigid sections including the sections 51 and 52 which have adjacent inter-engaged portions permitting longitudinal sliding of these sections relative to each other. The flexible shaft 50 is also provided with flexible couplings 53 interposed between sections thereof. The construction is such that rotations from the pulley 30 will be delivered to the hob shaft 39 in all possible positions of said hob shaft. It is pointed out that the hob shaft 39 moves horizontally, as well as vertically.

The hob shaft 39 may move horizontally because it is indirectly mounted on the hob support slide 28, which in turn is mounted on the horizontal hob feed slide 29 which moves horizontally. The hob feed slide 29 is mounted on horizontal ways 54, see Fig. 8, which are supported on the housing 20 of the machine. The vertical hob support slide 28 is supported for vertical movement by vertical ways 55, on the side of the hob feed slide 29.

The vertical position of the vertical hob support slide 28 is controlled by a micrometer 56. This micrometer is mounted on an overhead portion 57 of the vertical hob support slide 28 and normally rests upon a stop rod 58 which is mounted within the hob feed slide 29. The micrometer 56 may be adjusted so that the vertical hob support slide 28 is moved upwards and downwards in minute distances for controlling the depth that the hob 26 will cut the work 27. Means is provided for bodily lowering the stop rod 58 when the hob feed slide 29 reaches its finished position. This means includes a shaft 59 rotatively mounted on the hob feed slide 29 and turned by certain mechanism. This shaft 59 carries a cam 60 which engages a bottom section 61 of the stop rod 58. In one position of the shaft 59 the stop rod 58 is held in a raised position, and in a turned position of the shaft 59 the stop rod 58 will be in its lowered position. In the lowered position of the stop rod 58 the vertical hob support slide 28 will be in a down position and the hob 26 will be free from the work 27 so that the hob feed slide 29 may move to its starting position, and the hob will not collide and damage the finished work 27.

The stop rod 58 is formed from two sections; namely, the bottom section 61 and a tubular top section 62 which is rotatively supported on a flange 70 of the hob feed slide 29. The micrometer 56 engages this top section 62. The top section 62 is provided with a flange portion having gear teeth 63 which mesh with the teeth of a long vertical gear 64. This gear 64 is mounted on a spindle 65 having a head 66 accessible for manual turning. The bottom section 61 of the stop pin 58 is provided with a key 67 engaging a complementary slot in a flange 68 on the hob feed slide 29. The sections 61 and 62 are threadedly connected with each other by the threads 69. The construction is such that the head 66 may be manually turned for indirectly turning the section 62 of the stop rod 58 and causing it to be moved upwards or downwards to a selected position. With this construction it is possible to set the stop rod 58 to selected conditions. The micrometer 56 is used for fine adjustments.

The main drive pulley or wheel 30 is mounted on a shaft 73 which is rotatively supported on a flange 71 of the housing 20. Back of this flange 71 there are indexing change gears 72. More specifically, the pulley 30 which is mounted on

said shaft 73 connects with a gear 74 on said shaft 73. This gear 74 meshes with a gear 75 fixed to another gear 76. The gears 75 and 76 are rotatively supported upon an arm 77 which is pivotally mounted on said shaft 73. The arm 77 has a flange 79 engaged by a washer 80 which may be clamped down tightly by a cap screw 81 mounted on the flange 71. The construction is such that the cap screw 81 may be loosened and then the arm 77 is free to swing. A gear 82 is mounted on the shaft 78 and meshes with the gear 76. The construction is such that the gears 75 and 76 may be removed and replaced by other gears and these new gears may be properly meshed with the gears 74 and 82 by setting the arm 77 in a proper position.

The shaft 78 is rotatively supported in the housing 20 and extends from the back of the machine to the front of the machine and is provided with a spiral pinion 83 meshing with a spiral gear 84 on the head stock spindle 85 which supports the work arbor 24. The head stock spindle 85 is provided with another spiral gear 86 meshing with a spiral gear 87 on a rotatively supported shaft 88 which extends to the front of a flange 71' of the housing 20. The shaft 88 is provided with a gear 89 meshing with a gear 90 on a rearwardly extending shaft 91. The gears 89 and 90 are removable and changeable with other gears, and comprise feed change gears of the gear hobbing machine. The shaft 91 extends rearwards and is provided with a spiral gear 92 meshing with a spiral gear 93 mounted on the main feed slide shaft 94. This shaft 94 is rotatively supported in the housing 20 and is indirectly connected to drive the hob feed slide 29.

More specifically, the main shaft 94 is connected with a rotatively supported auxiliary shaft 95 by a friction clutch 96. The friction clutch 96 has a section 97 mounted on the shaft 94, and a complementary section 98 mounted on the shaft 95. A spring 99 acts between a flange 100 on the shaft 95 and a stationary bracket 101, and normally tends to urge the clutch 96 open. The clutch 96 is held closed by a screw 102. This screw 102 is threadedly mounted through a wall of the housing 20. It is provided with a hand wheel 103 by which it may be operated. The screw 102 is freely rotatively connected by a thrust bearing 104 with the adjacent end of the shaft 95. The construction is such that the hand wheel 103 may be turned in one direction for closing the clutch 96, and then rotations will be transmitted from the shaft 94 to the shaft 95. The hand wheel 103 may be turned in the other direction for turning the screw 102 outwards a small amount so that the spring 99 may open the clutch 96.

A spur gear 105 is mounted on the shaft 95 and meshes with a gear 106 mounted on the feed screw 107 of the hob feed slide 29. This screw 107 is rotatively supported and threadedly connects with a follower 108 which is connected with the feed slide 29. The feed slide 29 is provided with a flange 109 from which several rods 110 extend inwards through openings in a wall of the housing 20. Expansion springs 111 are mounted on the rods 110 and act against the housing 20 and flange 109 and normally urge the hob feed slide 29 to its starting position. When the clutch 96 is closed the shaft 94 is capable of turning the screw 107 and driving the hob feed slide 29 to its finished position. However, when the hand wheel 103 is manipulated to open the clutch 96 the springs 111 are then, and only

then, capable of forcing the hob feed slide 29 back to its starting position. During this operation the screw 107, which is a steep thread screw, merely turns.

The head stock spindle 85 is provided with a collet clutch 112 which supports the work arbor 24. The work arbor 25 is indirectly supported upon a tailstock spindle 113. This tailstock spindle 113 supports a bushing 114 which in turn supports the work arbor 25. A cap 115 is threadedly and removably mounted on the bushing 114. A rod 116 passes through the tailstock spindle 113 and has a reduced front end 117 which threadedly engages the inner end of the bushing 114. A steel ball 118 is located within the bushing 114 and engages against the adjacent end of the rod 116 and forms a thrust bearing for the work arbor 25. The outer end of the rod 116 is threaded and a nut 119 is threadedly mounted on this latter end and engages the end of the tailstock spindle 113.

A handle 120 radially projects from the tailstock spindle 113 and passes through a bayonet slot 121 in a tube 122 which is adjustably mounted on a support portion 123 of the housing 20. A set screw 124 holds the tube 122 in adjusted positions. The bayonet slot 121 has a longitudinally extending portion 125 and a transversely extending portion 126. When the handle 120 is in the transverse portion 126 the work arbor 25 will be in its operative position. The handle 120 may be moved to the free end of the longitudinal section 125 of the bayonet slot 121, and then the tailstock spindle 113 will be retracted and the work arbor 25 similarly moved.

The means for bodily lowering the stop rod 58 previously referred to when the hob feed slide 29 reaches its finished position, includes a handle 127 fixedly mounted on an extended end of the shaft 59. A catch 128 is also mounted on the shaft 59 and engages a complementary catch 129 pivotally mounted on a pintle 130 supported on the hob feed slide 129. The catch 129 has a tail 131 which is in line with a rod 132 adjustably mounted by a stationary clamp 133 mounted on the housing 20. A rod 134 pivotally connects with the handle 127 and extends downwards and pivotally connects with the operator lever 135 of a switch 136 which is connected to control the operation of the motor 32. The electrical connections of switch and motor will not be given in this specification as it forms no part of the invention, and such connections would be known to those skilled in the art.

The rod 134 is made of two sections adjustably connected by a coupler 137. The clamp 133 may be opened and the rod 132 adjusted to a selected position which will control the finished position of the hob feed slide 29. When the hob feed slide reaches its finished position the tail 131 of the hook 129 will strike the rod 132. This will pivot the hook 129 free from the hook 128. This releases the shaft 59 and the handle 127 will fall downwards, pivoting the shaft 59. This turns the cam 60 which drops the stop rod 58. At the same time when the handle 127 drops downwards, the rod 134 will operate the switch 136, stopping the electric motor 32.

The starting position of the hob feed slide 29 is controlled by a stationary stop 138 which is fixedly mounted on the hob feed slide 129 by a screw 139. A rod 140 is adjustably supported by a clamp 141 stationarily mounted on the housing 20. The construction is such that the

hob feed slide 29 may move towards the rod 140 until the stop 138 touches the rod 140. This is the starting position for the hob feed slide.

The index change gears 72 are located upon the back of the housing 20, while the feed change gears 89, 90 are located upon the front of the housing 20. A cover 143 normally extends over and covers the feed change gears 89, 90. Another cover 144 extends over and normally covers the index change gears 72. The cover 143 is supported on an arm 145 which extends along the side of the housing 20 and terminates in between a pair of horizontally spaced flanges 146 and 147 projecting from the housing 20. The cover 144 is supported by an arm 148 which extends along the side of the housing and in between the said flanges 146 and 147. A vertically slideable pin 149 passes through the flanges 146 and 147 and through the arm 145 and serves to pivotally support the arm. This pin 149 has a key 150 which in a raised position of the pin is free from the arm 145. However, the pin 149 may be moved to a lowered position and then it will engage a key opening 151 in the arm 145. A gear 152 is turnably mounted on the pin 149 and is provided with a key opening 153 aligned with the key opening 151 when the cover 143 is in its closed position and the gear 152 is in a certain position. The pin 149 is provided with heads at its top and bottom ends. A spring 154 is interposed between the bottom head and the flange 147 for normally urging the pin 149 downwards. The pin 149 is held in a raised position by the fact that the key 150 is resting on the top face of the arm 145.

The arm 148 is supported in substantially the identical way that the arm 145 is supported. There is another pin 149 which vertically slidably passes through the flanges 146 and 147 and which is provided with a key 150 engageable with key openings in the arm 148 and in a gear 152 mounted on the pin. A spring 154 normally urges the pin 149 downwards. A slide 156 is provided with rack teeth 157 along its sides which mesh with the gears 152. This slide 156 has a central opening 158 with rack teeth 159 along one side meshing with a gear 160. This gear 160 is mounted on a handle 161 which projects from the top flange 146. The top flange 146 is provided with openings 162, each extending through substantially 90° for accommodating the keys 150 when the pins 149 are in their raised positions. Each cover 143 and 144 is provided with a leaf spring latch 163 cooperative with an adjacent portion of the housing 20 for releasably holding the covers in their closed position.

When the pins 149 are in their bottom positions and the covers 143 and 144 are closed, the handle 161 may be turned to move the slide 156 towards the left, as illustrated in Fig. 13. The slide 156 will indirectly turn the gears 152 and since said gears are now keyed to the arms 145 and 148, said arms will be simultaneously pivoted and the covers 143 and 144 will be moved to open positions free from the change gears. The change gears may now be changed, as required. Then the handle 161 may be turned in the other direction to move the slide 156 back to its initial position which will indirectly cause the covers 143 and 144 to be moved back to their closed positions. If it is desired to open but one of said covers, that is the cover 143, or the cover 144 without disturbing the other of the covers, it is merely necessary to move the particular pin

149 of the particular arm (arm 145 or arm 148) of the particular covers upwards to its raised position and then turn said pin 149 90° so that the key 150 thereof now rests on said arm, holding the pin 149 raised. Now the handle 161 may be turned for again driving the slide 156 towards the right as illustrated in Fig. 13. The gears 152 will turn, but since only one of the gears is keyed to one of said arms, that particular arm will be turned and the particular cover will be opened. This cover may be reclosed and the pin 149 which is raised, moved back to its lowered position, and the device is now back in its original condition.

The operation of the gear hobbing machine is as follows:

Rotations from the motor 32 will drive the pulley 30, which in turn will drive the hob shaft 39 driving the hob 26. Simultaneously, rotations from the pulley 30, through the index change gears 72 and the spiral gears 83 and 84 will drive the head stock spindle 85. The head stock spindle 85 drives the work arbors 24 and 25. Simultaneously, while this is happening, rotations of the head stock spindle 85 through the gears 86 and 87 and the feed change gears 89 and 90, will indirectly drive the hob feed slide main shaft 94. The rotations from said shaft 94 will be transmitted by the friction clutch 96 to indirectly drive the hob feed slide 29. The hob 26 is now cutting the work 27. When the hob feed slide 29 reaches its finished position the work 27 will be finished. In the finished position of the hob feed slide 29, the tail 131 of the hook 129 will engage the rod 132 which indirectly will cause turning of the shaft 59 which will drop the vertical hob feed slide 28. At the same time turning of the shaft 59 will indirectly operate the switch 136, cutting off the motor 32. The machine has now finished its work.

The hand wheel 103 may now be turned to open the clutch 96. The springs 111 will immediately return the hob feed slide 29 to its starting position. The handle 120 may be manipulated to release the work 27. New work is now placed between the arbors 24 and 25. The handle 127 is now turned back to its original position which turns the shaft 59, which raises the stop rod 58 which indirectly moves the hob support slide 28 back to its raised position. When the handle 127 was raised, the switch 136 was indirectly closed, re-starting the motor 32 and the machine is now starting its operation on the new work.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In a gear hobbing machine, a horizontal hob feed slide, means for driving said hob feed slide to a finish position, a vertical hob support slide mounted on said hob feed slide, a stop rod vertically slidably mounted on said hob feed slide, a height adjustment micrometer mounted on said hob support slide and resting on said stop rod, and means for bodily lowering said stop rod when said hob feed slide reaches its finish position.

2. In a gear hobbing machine, a horizontal

hob feed slide, means for driving said hob feed slide to a finish position, a vertical hob support slide mounted on said hob feed slide, a stop rod vertically slidably mounted on said hob feed slide, a height adjustment micrometer mounted on said hob support slide and resting on said stop rod, and means for bodily lowering said stop rod when said hob feed slide reaches its finish position, said stop rod having a top end portion vertically adjustably mounted on a bottom portion, and said micrometer being supported by said top end portion.

3. In a gear hobbing machine, a horizontal hob feed slide, means for driving said hob feed slide to a finish position, a vertical hob support slide mounted on said hob feed slide, a stop rod vertically slidably mounted on said hob feed slide, a height adjustment micrometer mounted on said hob support slide and resting on said stop rod, and means for bodily lowering said stop rod when said hob feed slide reaches its finish position, said stop rod having a top end portion vertically adjustably mounted on a bottom portion, and said micrometer being supported by said top end portion, said top end portion being threadedly mounted on said bottom portion, and means for rotating said top end portion relative to the bottom portion for attaining said vertical adjustment.

4. In a gear hobbing machine, a horizontal hob feed slide, means for driving said hob feed slide to a finish position, a vertical hob support slide mounted on said hob feed slide, a stop rod vertically slidably mounted on said hob feed slide, a height adjustment micrometer mounted on said hob support slide and resting on said stop rod, and means for bodily lowering said stop rod when said hob feed slide reaches its finish position, said stop rod having a top end portion vertically adjustably mounted on a bottom portion, and said micrometer being supported by said top end portion, said top end portion being threadedly mounted on said bottom portion, and means for rotating said top end portion relative to the bottom portion for attaining said vertical adjustment, said last named means comprising a gear portion on said top end portion, another gear meshing with said gear portion and adapted to be manually turned.

5. In a gear hobbing machine, a horizontal hob feed slide, a vertical hob support slide mounted on said hob feed slide, a hob shaft rotatively mounted on said hob support slide, a rotative drive pulley located backwards of said hob shaft, said hob shaft being mounted in a bearing, said bearing being pivotally supported to pivot in a horizontal plane, means for releasably clamping said bearing in selected pivoted positions, and means for adjusting said bearing to selected positions, comprising resilient means tending to pivot said bearing in one direction, and an adjustment screw for holding said bearing in various selected positions against the action of said spring.

6. In a gear hobbing machine, a horizontal hob feed slide, a vertical hob support slide mounted on said hob feed slide, a hob shaft rotatively mounted on said hob support slide, a rotative drive pulley located backwards of said hob shaft, and a flexible shaft connecting said drive pulley and hob shaft, said hob shaft being mounted in a bearing, said bearing being pivotally supported to pivot in a horizontal plane, means for releasably clamping said bearing in selected pivoted positions, and means for adjusting said bearing to selected positions, comprising a lug projecting from the bearing, an adjustment screw engaging against said lug for moving the bearing to various positions, and resilient means tending to pivot said bearing to hold its lugs engaged against said adjustment screw.

7. In a gear hobbing machine, a pair of opposed work arbors for holding work between them, a driven headstock spindle supporting one of said arbors, a tailstock spindle for the other arbor, a bushing surrounding said last mentioned arbor and extending into said tailstock, a rod mounted through said tailstock spindle and connected with said bushing, and a steel ball within said bushing and engaging against an adjacent end of said rod and arbor.

8. In a gear hobbing machine, a horizontal hob feed slide, a steep angle hob feed screw beneath said slide, a follower from said slide engaging said screw, resilient means urging said hob feed slide to a starting position, a hob feed drive shaft, a transmission from said drive shaft to said screw and including a clutch, and means for opening said clutch, whereby said resilient means returns said hob feed slide to its starting position.

9. In a gear hobbing machine, a horizontal hob feed slide, a steep angle hob feed screw beneath said slide, a follower from said slide engaging said screw, resilient means urging said hob feed slide to a starting position, a hob feed drive shaft, a transmission from said drive shaft to said screw and including a clutch, and means for opening said clutch, whereby said resilient means returns said hob feed slide to its starting position, comprising resilient means tending to open said clutch, and a screw opposed to said resilient means for holding said clutch closed.

10. In a gear hobbing machine, a horizontal hob feed slide, a steep angle hob feed screw beneath said slide, a follower from said slide engaging said screw, resilient means urging said hob feed slide to a starting position, a hob feed drive shaft, a transmission from said drive shaft to said screw and including a clutch, and means for opening said clutch, whereby said resilient means returns said hob feed slide to its starting position, said resilient means comprising expansion springs acting between said hob feed slide and a stationary part of said gear hobbing machine.
